UNITED STATES PATENT OFFICE.

ELMER ELSWORTH MACK, OF FORT SCOTT, KANSAS.

AUTOMATIC WINDOW-FASTENER.

1,242,830.

Specification of Letters Patent.

Patented Oct. 9, 1917.

Application filed July 30, 1917. Serial No. 183,512.

To all whom it may concern:

Be it known that I, ELMER E. MACK, a citizen of the United States, residing at Fort Scott, in the county of Bourbon and State 5 of Kansas, have invented a new and useful Automatic Window-Fastener, of which the following is a specification.

The subject of this invention is a window lock designed to automatically lock a window sash against movement, and the objects 10 of the invention are, first to provide a latch which will automatically lock the upper and lower sash, second, to provide a latch on one sash adapted to coöperate with catches on 15 the other sash and on the window stop, third, to provide a simple and efficient window latch.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed, can be made within the scope of what is claimed, without departing from the spirit of the invention.

A practical embodiment of the invention 30 is shown in the accompanying drawings, wherein:

Figure 1 is a perspective view of the device showing the same attached to a window, a fragmentary portion of which is 35 shown.

Fig. 2 is a plan view of the latch, the casing being in section.

Fig. 3 is a perspective view of one catch.

Fig. 4 is a perspective view of the other 40 catch.

Referring to the drawing by numerals of reference:

The ordinary window frame is shown at 1 on which is mounted the usual window 45 stop 2 which with the spacing or dividing strip 3 forms a channel in which the lower sash 4 may slide. The upper sash 5 is slidably mounted in the frame in the usual way, and is retained in place therein by the 50 strip 3.

Secured on the end of the upper cross piece of the lower sash is a latch comprising a casing 6 within which reciprocates a block or plate 7 which is formed with extending 55 arms 8 at diagonally opposed corners. The

arms 8 extend through openings 9 formed in the casing 6.

A stem 10 projects from one end of the plate 7 and passes through a suitable aperture formed in the end of the casing 6. A 60 coiled spring 11 surrounds the stem and yieldably retains the plate 7 in its normal or forward position. A headed pin 12 rises from the plate 7, to which it is fastened in any suitable manner, and extends through a 65 slot 13 formed in the casing 6. This pin acts as a thumb piece or finger grip by which the plate 7 may be reciprocated.

A wedge shaped block 14 is provided on one edge with spurs 15, and the block has 70 a suitable aperture 16 for the reception of a nail or screw by which it may be secured to the stop 2, the spurs being positioned to enter the stop and prevent the block from turning on the nail or screw. This block 75 forms a catch for one of the arms 8 of the latch.

Another wedge shaped block 17 is provided on one side or face with the spurs 18, and has an aperture 19 extending transversely thereof for the reception of a nail 80 or screw by which the block is fastened to the face of a side bar of the upper sash 5. The spurs 18 act as an anchor for the block to prevent its pivoting on the nail or screw. 85

In practice the device operates as follows: The latch is secured to the lower sash by screws or otherwise, and the catches secured in place on the sash stop and the upper sash. It will be understood that the catches may 90 be spaced at intervals along the stop and upper sash if desired. When both sashes are closed, as shown in Fig. 1, the arms 8 of the latch lie under the catches or blocks 14 and 17 and prevent one opening the window 95 without first releasing the latch.

The latch may be released by pressing outwardly on the pin 12 and forcing the plate 7 outwardly which will draw the arms 8 from under the blocks or catches. Either 100 sash may then be moved to any desired position and, should other catches be provided, may be locked in any selected position.

Having thus described the invention, what is claimed as new and sought by Letters Patent, is:

1. A window fastener, comprising in combination with a window frame and sashes, a casing secured to the lower sash, a resiliently held plate sliding in the casing, arms extend- 110

ing from the plate, a thumb piece for actuating the plate, a wedge shaped catch secured to the sash stop, and a wedge shaped catch secured to the upper sash, said catches 5 adapted to overlie the arms when the plate is in normal position.

2. A window fastener comprising, in combination with a window frame and sashes, a resiliently held plate slidable on the lower 10 sash, latching arms extending from opposed

edges of the plate, and catches on the frame and upper sash adapted to overlie the arms and lock the sashes against movement.

In testimony that I claim the foregoing as my own, I have hereto affixed my signature in the presence of two witnesses.

ELMER ELSWORTH MACK.
